BOX FOR HOLDING COSMETIC PREPARATIONS AND TOOLS AND THE LIKE

Andrew Lutz, Chicago, Ill., assignor to F. H. Noble & Co., Chicago, Ill., a corporation of Illinois

Application April 17, 1939, Serial No. 268,252

5 Claims. (Cl. 206—12)

My invention relates to a novel container which I have devised, consisting of a body member and a cover hinged thereto, and a tray within the box body which is arranged to be automatically erected to inclined position for convenient use or display of articles contained therein when the lid of the box is raised, and to be automatically restored to its seat within the box when the lid is closed. The general object of my invention is the production of a box of this character, and the provision of suitable and efficient mechanical elements and members through which the box parts are connected and the desired movement of the tray brought about. My invention resides in the novel organization and arrangement of the box members and associated connecting elements, cooperating to effect the results desired, the essential elements of my invention being more particularly pointed out in the appended claims.

In the accompanying drawing I have illustrated my invention embodied in a small case suitable for conveniently holding a set of bottles or boxes and an assortment of tools and implements such as used by manicurists or chiropodists, though obviously my invention is adapted to various other uses. In the drawing, Figure 1 is a perspective view of the case, with the cover member raised and the tray in erect position; Fig. 2 is a vertical cross-section of the same; Fig. 3 is a cross-section with the cover closed; Fig. 4 is a fragmentary detail on a larger scale through one of the spring hinges by which the box members are pivotally connected; and Fig. 5 is a fragmentary plan view of the rear portion of the box with the cover member raised.

Like reference characters indicate like parts in all the figures of the drawing.

While the specific construction of the box member may vary widely, the body member may conveniently be formed of a flanged sheet metal member 1 having its bottom and side and end portions covered with a sheet of leather or cloth 2 providing an ornamental finish. The cover member 3 may be similarly formed, and, as shown, a rounded pad 4 may be employed between the top section and the finishing sheet 5 to enhance the ornamental appearance of the box.

The box body and cover are hinged together, in the present instance, by a pair of spring hinges 6, of well known construction, one near each end of the box, and provided with C-shaped springs 7 arranged to stress the cover alternatively either to closed position when the cover is closed, or to

open position when the cover is open beyond a dead center line of stress.

If desired, the body member may be lined with an inside ply of lining material 8 and an ornamental lining strip 9 extending around the inside faces of the end and front side walls of the body member, as shown on the drawing.

Secured to the inside of the cover of the box is a cloth finished cardboard panel 10, which is held in place by any suitable fastening means, as by means of tongues struck up from the metal cover member and clinched over the edges of the panel member beneath its finishing fabric. To the panel 10 is secured a sheet metal rack 11 formed with clasps 12 struck up from the body 10 of the plate and suitably formed to engage and clasp the various tools and implements suitable for the purposes of the operator for whose use the case is designed. This rack in the present instance is secured in place by means of marginal tongues 13 extending through the panel 10 and a sheet metal member 14 disposed between said panel and the inner face of the cover member which is provided to afford additional stiffness and rigidity to the structure.

The collapsible tray structure which constitutes an important part of my invention will next be described. The tray proper is in the present instance formed of a single piece of sheet metal having a back panel 15 and a bottom 16, 30 and connected with said bottom end flanges 17 and a front retaining flange 18 which may be bent as shown to provide a plurality of seats conforming to the shape of the bases of the bottles A, which the tray is formed to receive. The back 35 15 of the tray is preferably formed with a plurality of spring tongues which provide for a yielding grip upon the bottles seated in the sections of the tray.

The top of the tray member 15 is hinged to a bracket member 19 of the somewhat irregular outline in cross section shown best in Fig. 2, which extends forwardly,—i. e., towards the front side of the box,—and which is rigidly secured to the rear side of the cover member of the box in 40 suitable manner, as by soldering or riveting. In the present instance, to provide for securing the bracket to the cover member, the bracket is formed with an outer attaching section 20 45 conforming in contour to the portion of the cover member next to it; an intermediate section 21 extending substantially at right angles to such attaching section and conforming generally to the shape of the rear walls of the cover and box body, and an end section 22 extending at right 50 55 angles to the intermediate section 21.

- angles to such intermediate section and connected by the hinge joint mentioned with the top or rear of the tray member. The arrangement is such that when the cover is opened the forward, bottom edge of the tray, after a slight forward movement, will ride rearwardly on the inner face of the bottom of the box, and when the cover is open the tray will assume the inclined position shown in Fig. 2. It will be noted that the right-angled bend between the lower part of the intermediate section and the hinging section provides space to accommodate the stopper of the bottle when the case is closed, and practically all of the space within the box body is thereby rendered available.
- Forwardly of the tray within the box body an additional stationary tray or support 23 may be provided for additional tools, or other supplies, if desired.
- 20 As illustrated, the exposed portions of the hinges and parts of the rear flanges of the box body and cover members adjacent thereto may be covered with an ornamental strip of fabric 24, to provide a better finish.
- 25 By modification of proportions and dimensions of the parts, it is possible to vary the specific construction above described to adapt my invention to various other uses and purposes, and I, therefore, desire my claims construed to include 30 such variations to adapt my invention to other uses to which it may be applicable.
- I claim:
1. In a container, a box body, a cover member hinged to said box body, a rigid bracket member rigidly secured to said cover member and extending from a point adjacent the axis of the box hinges downwardly and forwardly to a point which is adjacent the bottom of the box body and is spaced from the rear of the box when the 40 cover member is closed, a tray within said box body hingedly connected at the rear side of its back portion to the forward edge of said bracket member, the forward edge of said tray being arranged to ride slidably over the bottom of the box body when said cover member is raised and the tray shifted to inclined position.
  2. A container according to claim 1 in which the bracket member is formed with an intermediate section arranged when the cover is in 50 closed position to extend adjacent to the rear wall

of the box body and with an angularly connected end section arranged to extend adjacent the proximate rear portion of the bottom of the box body.

3. In a container, a box body formed with a bottom and connected side and end walls, a cover member formed with a top and connected side and end walls hinged along one side wall to the proximate side wall of said box body, a forwardly extending bracket member having an attaching section rigidly secured to the rear of said cover member and an intermediate section arranged when the cover member is in closed position to extend adjacent the rear side walls of the cover member and box body and an end section arranged when the cover member is in closed position to extend adjacent the rear portion of the bottom of the box body, a tray within said box body hinged at its rear to the front end of said end section of the bracket member, said tray being arranged to ride on the bottom of said box body to inclined position when said cover member of the box is raised.

4. A container according to claim 3 in which said tray comprises a rear panel and a bottom and end and front flanges adjacent said bottom forming bottle seats, said rear panel forming a support for the back of supported bottles, and said end and front flanges being arranged to extend over the base portion only of such bottles, and the angular space between the attaching and 30 intermediate sections of said bracket member being formed to provide space for reception of the neck portions of such bottles when the box is in closed position.

5. A container according to claim 3 in which 35 said tray is formed of sheet metal and comprises a rear panel and a bottom and end and front flanges adjacent said bottom forming bottle seats and the sheet metal material of said tray is formed with retaining portions for frictionally holding bottles in said seats, said rear panel forming a support for the back of supported bottles, and said end and front flanges being arranged to extend over the base portion only of such bottles, and the angular space between the attaching 45 and intermediate sections of said bracket member being formed to provide space for reception of the neck portions of such bottles when the box is in closed position.

ANDREW LUTZ. 50
